COMBINED CABINET, SINK AND TABLE UNIT FOR USE IN A HOSPITAL

William J. Hannon, Jr., Dorchester, Mass., assignor to
The MacBick Company, Cambridge, Mass., a corpora-
tion of Massachusetts

Filed Mar. 6, 1962, Ser. No. 69,110

Term of patent 14 years

(Cl. D16—2)

FIG. 1

FIG. 2

FIG. 3

FIG. 1 is a front perspective view of a combined cabinet, sink and table for unit for use in a hospital embodying my new design;

FIG. 2 is a plan view of the unit of FIG. 1;

FIG. 3 is a rear perspective view of the unit of FIG. 1;

The dominant features of my design reside in those portions shown in full lines in the drawings.

I claim:

The ornamental design for a combined cabinet, sink and table unit for use in a hospital, substantially as shown and described.
